UNITED STATES PATENT OFFICE.

JOHN T. SWEENEY, OF KINGSTON, NEW YORK, ASSIGNOR TO W. G. BROWNE MFG. CO.,
OF NEW YORK, N. Y., A CORPORATION OF NEW YORK.

TAPE-MEASURE.

1,096,963.

Specification of Letters Patent. Patented May 19, 1914.

Application filed May 26, 1913. Serial No. 769,825.

To all whom it may concern:

Be it known that I, JOHN T. SWEENEY, a citizen of the United States, residing at Kingston, in the county of Ulster and State 5 of New York, have invented certain new and useful Improvements in Tape-Measures, of which the following is a specification, reference being had therein to the accompanying drawings, which form a part 10 thereof.

My invention relates to tape measures, and more particularly to a type thereof employing a reel upon which a tape is adapted to be wound.

15 The main object of the invention is to provide a tape measure wherein the reel will be supported within a casing in a manner to minimize wear upon the casing while at the same time preventing the collapsing of 20 the casing adjacent to the reel.

A further object is to provide a tape measure wherein a rewinding handle is provided, which will act at long leverage while being collapsible within the casing in a manner 25 to avoid such protuberances as would interfere with the handling and carrying of the device when not in use.

A still further object is to provide a tape 30 measure wherein the rewinding handle when extended will be so held as to prevent any frictional engagement thereof with the outer casing over which it projects, while at the same time permitting said handle to be readily folded within the reel so as to be wholly 35 within the plane of the casing.

A still further object is to provide a tape 40 measure wherein the central portion of the casing has an opening therethrough, and the opposite portions of the reel are connected by a reinforcing bar in a manner to stiffen the reel, said bar being also adapted to carry a pivotally supported handle, which when in use is adapted to be unfolded 45 outwardly so as to increase the leverage during rewinding, and when not in use to be folded and retained within said reinforcing cross bar. And a still further object is to provide a tape measure which may be 50 economically produced, and which will be durable in use.

The invention consists primarily in a tape measure embodying therein a casing, consisting of two annular sections having outer and inner parallel side flanges, the

latter of which are narrower than the former, whereby a continuous channel is formed about the opening of said casing, an annular reel seated within said casing and closing the space between said inner flanges, said reel having outwardly turned parallel 60 flanges bearing upon said outer casing, whereby said casing is supported adjacent the opening at the center thereof and the cutting of said casing by said reel is prevented, means carried by said reel whereby a flexible 65 tape may be secured thereto, and rewinding means projecting between the inner flanges of said casing sections and connected to said reel; and in such other novel features of construction and combination of parts as 70 are hereinafter set forth and described, and more particularly pointed out in the claims hereto appended.

Referring to the drawings:—Figure 1 is 75 a plan view of a tape measure embodying my invention, a portion of the top casing being broken away and the rewinding handle being shown in the extended position; Fig. 2 is a sectional view thereof; Fig. 3 is a view similar to Fig. 1 with the rewinding 80 handle folded within the casing and the reel broken away to show the means for attaching the tape thereto; and Fig. 4 is a detail view of the reinforcing cross bar and the rewinding handle.

Like letters refer to like parts throughout the several views.

In the embodiment of my invention shown in the drawings, a metallic casing is provided consisting of two annular sections *a* 90 and *b*, provided with the outer side flanges *a'* and *b'*, said outer side flanges being provided with the extensions *a²* *b²* adapted to be crimped or upset in a manner to secure the said sections together. Each section *a* *b* 95 is also provided with a central opening as shown in Figs. 1 to 3, and adjacent to said opening there is an inner annular flange *a³* *b³* considerably shorter than the flanges *a'* *b'* so as to leave a continuous channel within 100 the central opening of the casing. Closing this channel is the reel *c* adapted to seat and revolve upon the flanges *a³* *b³*. This construction is old and well known in the art, and it is not my intention to claim such 105 broadly at this time. In practice, all of the parts heretofore described have been made of sheet metal and in use there has been a

tendency of the reel *c* to cut the ends of the casing, thus destroying the measure, as this cutting causes rough edges calculated to lacerate the hand of the user.

- 5 To avoid the cutting of the casing sections by the reel *c*, I provide said reel at each edge thereof with flanges *d* and *e* extending at substantially right angles thereto, which flanges present an extended bearing surface 10 contacting with said sections *a* *b* adjacent the flanges *a*³ *b*³. By this construction, the sections *a* *b* will be supported adjacent the central opening in a manner which will avoid any possibility of pressure upon said 15 casing resulting in the abrasion or cutting of said sections. Intermediate the flanges *d* and *e* the reel or ring *c* is provided with a tongue *c'*, to which the end of the tape *f* is permanently attached.
- 20 Extending across the opening at the center of the sections *a* *b* is a reinforcing channel bar *g* provided with end tongues *g'* adapted to be inserted through openings in the ring or reel *c* and upset, said bar projecting between the inner channel between the flanges *a*³ and *b*³, thus having a clear field of rotation. I use a channel bar because this is inexpensive to produce, possesses the requisite rigidity, may be conveniently and firmly 25 attached to the reel, and will permit the application thereto of a pivoted rewinding stem which when not in use may be folded within this channel in a manner to bring all parts thereof within the outer plane of the 30 casing. This handle is shown at *h* and comprises a bar having parallel sections *h'* *h*² connected by an angularly arranged section *h*³. The section *h'* is pivoted at *i* within the channel bar *g*, and the section *h*² is provided with an ordinary swivel grip *j*. This handle is of a length so that when extended it will project adjacent to, or beyond, the periphery of the casing, and thus materially increase the leverage exerted thereby over 35 the old type of reinforcing bar. When the handle is in use and extended, the angular section *h*³ will hold the section *h*² projecting across the casing out of engagement therewith, and the section *h'* adjacent the pivot *i* will seat firmly within the channel bar *g* and thus relieve said pivot of all the stresses 40 from said handle, which stresses will be applied by the angular section *h*³ of said bar adjacent to the reel *c*. The cross bar *g* has in the bottom thereof an opening *g*² through which the handle *j* is adapted to pass when the handle *h* is folded.
- 45 The flanges *a'* *b'* are provided with the ordinary opening *l* through which the end 50 of the tape projects, said projecting end being provided with the usual stop piece *k*.
- 55 A tape measure made in accordance with my invention possesses the advantages of affording an extended bearing for the reel both against the flanges *b*³ and *a*³ and

against the top and bottom of the casing through the flanges *d* *e*. Cutting of the casing is absolutely prevented, and the reel is held so as to cause it to have a free and perfectly true rotation.

70 The construction of the cross bar *g* is such as to prevent the spreading of the reel while permitting it to be firmly and permanently secured in place by the integral tongues heretofore referred to.

75 The use of a channeled reinforcing bar not only gives the desired rigidity to the bar, and the stability to the reel, but affords a suitable housing for the extensible crank handle used for rewinding. The angular construction of this crank handle not only permits it to be folded within the casing when not in use, but also applies the rewinding power at the maximum leverage upon the bar *g* in a manner to prevent any likelihood of this handle being separated from said bar. At the same time when the handle is in use, it is held out of frictional engagement with the casing.

80 On the smaller sizes of tape measures, the handle *h* may be dispensed with if desired, although I prefer to use such upon all sizes.

85 It is not my intention to limit the invention to the precise details of construction shown in the accompanying drawings, it being apparent that such may be varied without departing from the spirit and scope of the invention.

90 Having described my invention, what I claim as new and desire to have protected by Letters Patent, is:—

1. A tape measure embodying therein a casing consisting of two annular sections having outer and inner parallel side flanges, the latter of which are narrower than the former, whereby a continuous slot is formed about the center of said casing, an annular reel seated within said casing and closing the slot between said inner flanges, said reel having outwardly turned parallel flanges at the edges thereof bearing upon the casing adjacent the center thereof, whereby the cutting of said casing by said reel is prevented, means carried by said reel whereby a flexible tape may be secured thereto, and rewinding means projecting between the inner flanges of said casing sections and connected to said reel.

105 2. A tape measure embodying therein a casing having a central opening there- 110 through, a continuous slot extending circumferentially about the wall of said casing adjacent said opening, an annular reel seated within said casing and closing said slot, said reel having outwardly turned parallel flanges at the edges thereof bearing upon the casing adjacent the opening in the center thereof, whereby the cutting of said casing by said reel is prevented, means carried 115 by said reel whereby a flexible tape may be 120

- 125 60 of the tape projects, said projecting end being provided with the usual stop piece *k*.

65 A tape measure made in accordance with my invention possesses the advantages of affording an extended bearing for the reel both against the flanges *b*³ and *a*³ and

secured thereto, and rewinding means projecting between the inner flanges of said casing sections and connected to said reel.

3. A tape measure embodying therein a casing having a central opening therethrough, the wall about said opening having a continuous slot, a reel rotatably mounted within said casing and closing said slot, means carried by said reel whereby a flexible tape may be secured thereto, a channelled cross bar extending diametrically across said opening and having its ends connected with said reel, and a handle pivotally mounted within said cross bar.

15 4. A tape measure embodying therein a casing having a central opening therethrough, the wall about said opening having a continuous slot, a reel formed of a metal strip rotatably mounted within said casing and closing said slot, means carried by said reel whereby a flexible tape may be secured thereto, a channelled cross bar extending diametrically across said opening and having its ends connected with said reel, and a handle pivotally mounted within said cross bar, said handle comprising two parallel sections, one of which when said handle is unfolded is adapted to seat within said channelled cross bar and upon the bottom thereof, and the other of which is adapted to project over said casing, and an intermediate section extending at substantially right angles to said first named section and connecting said parallel sections, whereby said handle when unfolded is held out of engagement with said casing.

5. A tape measure embodying therein a casing having a central opening therethrough, the wall about said opening having a continuous slot, a reel rotatably mounted within said casing and closing said slot, means carried by said reel whereby a flexible tape may be secured thereto, a channelled cross bar extending diametrically across said opening and having its ends connected with said reel, and a handle pivotally mounted within said cross bar, said handle comprising

ing a section adapted to be seated within said channelled bar when said handle is unfolded whereby all strains on said handle will be transmitted directly to said cross bar, a section adapted to project over said casing whereby the effective leverage of said handle is increased, and an intermediate section connecting the two first named sections.

6. A tape measure embodying therein a casing having a central opening therethrough, the wall about said opening having a continuous slot, a reel rotatably mounted within said casing and closing said slot, means carried by said reel whereby a flexible tape may be secured thereto, a channelled cross bar extending diametrically across said opening and having its ends connected with said reel, and a handle pivotally mounted within said cross bar, said handle comprising two parallel sections, one of which when said handle is unfolded is adapted to seat within said channelled cross bar and upon the bottom thereof, and the other of which is adapted to project over said casing, and an intermediate section extending at substantially right angles to said first named section and connecting said parallel sections, whereby said handle when unfolded is held out of engagement with said casing.

In witness whereof, I have hereunto affixed my signature, in the presence of two subscribing witnesses, this 6th day of May, 1913.

JOHN T. SWEENEY.
